CLAIM

The ornamental design for a monitor stand, as shown and described.

DESCRIPTION

FIG. 1 is a front view of a monitor stand;

FIG. 2 is a rear view of a monitor stand;

FIG. 3 is a top view of a monitor stand;

FIG. 4 is a bottom view of a monitor stand;

FIG. 5 is an upper rear perspective view of a monitor stand;

FIG. 6 is an upper front perspective view of a monitor stand;

FIG. 7 is a lower rear perspective view of a monitor stand;

FIG. 8 is a lower front perspective view of a monitor stand;

FIG. 9 is first side view of a monitor stand;

FIG. 10 is a second side view of a monitor stand; and,

FIG. 11 is an environmental view of a monitor stand with a mounted monitor.

In the drawings, the broken lines in the drawings illustrate environmental subject matter and form no part of the claimed design.
